ELECTRICAL FUSE

June L. Lehnher, Eldorado, Kans., assignor to
 Westinghouse Electric & Manufacturing Com-
 pany, East Pittsburgh, Pa., a corporation of
 Pennsylvania

Application February 15, 1932, Serial No. 592,947
 Renewed October 17, 1935

7 Claims. (Cl. 200—117)

This invention relates to an improvement in electrical fuses such as are used in connection with transformers, power transmission lines and the like, although they may be designed for other purposes as will be later explained.

5 Fuses for use as above mentioned have been made before but they have not been altogether satisfactory as their working parts have been interfered with by weather conditions, such as ice 10 freezing in the working parts which prevents action of the parts and defeats the purpose of the fuse. This trouble is overcome by the use of my improved device.

15 My improved fuse device does away with set screws, bolts, etc., leaving the exterior of the fuse tube neat and doing away with the demand for special tools in reloading the fuse.

20 Another feature of my improved fuse device is that after the parts of the fuse are assembled, the fuse tube is closed so that it is tight and practically weather proof, thereby keeping the interior of the tube dry and the parts therein in operative condition at all times. The fuse tube being so closed also prevents insects, dust, or other matter 25 entering or collecting in the tube which might interfere with the function of the fuse.

25 A further feature of my improved fuse device is that the fuse element is held in tension in the center of the fuse tube or barrel thereby eliminating the burning of the barrel by the heat of the fuse element.

30 Another feature of my invention is that the fuse assembly is entirely self contained and no part of the fuse link itself, or "pig-tail" connector is exposed to the weather. This feature eliminates 35 corrosion of the metal or crystallization from wind vibration.

35 A still further feature of my improved fuse device is that the hammer or impact principle embodied therein insures positive clearance of the interior of the tube of all metallic elements, separating the two parts of the electric circuit by the full length of the non-conducting fibre or composition tube.

40 Another feature of my invention is that the device provides a simple method of refusing the tube by a simple positive means, and the device is adaptable to fuses of any size and for tubes which are enclosed in an exterior housing as well as 45 tubes exposed to the weather.

45 A still further feature of my improved fuse is that through the impact or kinetic energy of the device in expelling itself from the tube it may be used to operate ratchets, pawls or relays to accomplish 50 any number or train of operations desired 55

incident to the failure of the fuse. For instance, the failure of the fuse might set off an alarm system, or it might, in the case of the blowing of one fuse, operate a relay which would open the other phases of a polyphase circuit.

5 Another feature of my invention is that it permits the use of a very short fuse element, thus reducing the cost of refusing. My device may also be used over and over again and will provide over-load protection as well as fuse protection.

10 My device will extend the field of fuses and will invade the oil circuit breaker field since it will provide a simple, economical means of quickly breaking an electrical circuit.

15 This device will find its place in fusing of power or potential transformers, line sectionalizing or wherever it is desirable to interrupt an electric current at a predetermined rate of current flow.

20 While the internal parts of my fuse device are self expelling they will have the assistance of gravity, or the explosion of the fuse in the chamber, or both, in assisting to make a quick interruption of the circuit.

25 My device provides, through the positive shock or impact of the spring or plunger, certain operation of the fuse for outdoor fuses during sleet or ice storms. Another advantage is that the lower or contact and sealing plug can be recessed slightly so as to minimize the forming of ice at the joint between the contact plug and the fuse housing. 30 However, even though ice may form at this location, the positive action of the device will break any ice formed and insure the clearing of the fuse tube of all metallic content. This is particularly desirable on disconnect or sectionalizing 35 switches which depend for their rupturing power on the drop out principle of the entire fuse assembly. In case of sleet, the toggle or other mechanical arrangement holding the fuse assembly in place may freeze up and fail to operate. The 40 use of my self expulsion mechanical device will insure the rupturing of the fuse.

45 There may be cases where it is inadvisable to have the fuse device completely expelled from the tube. In this case, however, the spring action involved will insure the enlargement of the gap after the failure of the fuse element.

50 The construction of this fuse device and its assembly with the other elements to make up the complete fuse are such that it gives a positive continuous metallic circuit from one end of the fuse to the other thus eliminating radio interference, which is a common defect of many types of fuse.

55 Now referring to the drawings in which like

symbols indicate the same part throughout the several figures, Fig. 1 is a side view of my improved fuse device installed ready for operation. Fig. 2 is a sectional view of my improved fuse device showing the several parts and assembly thereof. Fig. 3 is a sectional view of my fuse assembly as seen from the line 111-111 in Fig. 1. Fig. 4 is a plan view of Fig. 2. Fig. 5 is a side view of the spring and plunger device in contracted position. Fig. 6 is a plan view of the centering device employed in holding the fuse on the center axis of the fuse barrel. Figs. 7 and 8 are views showing modified forms of plunger or impact producing mechanism. Fig. 9 is a view illustrating the application of my invention to operate or set off a signal or any other operation or train of operations. Fig. 10 is a view showing my improved fuse device as being used where the fuse would be ruptured by heat from a fire instead of an electric current, and also illustrating a train of operations that would be actuated by the fuse device upon the failure of the fuse. Fig. 11 is a sectional view of my improved fuse device as seen from the line XI-XI in Fig. 10.

In the drawings is shown an enclosure or tube 10 which is a non-conductor of electricity. On the bottom end of the tube 10 is a metallic ferrule 11 rigidly attached to the tube 10. The lower internal portion of the ferrule 11 is flared as at 12 to receive a tapered plug 13 on which is rigidly affixed a metallic tubelike element 14 having a slot 15 therein. Slidably mounted in the tube 14 is a metallic rod 16 around which is a helical spring 17, one end of which is rigidly attached by solder or any other suitable means at 18 to the upper end of the rod 16. The opposite or lower end of the spring 17 is rigidly attached at 19 by solder or any other suitable means to the upper end of the tube 14. The lower end 10 of the rod 16 is provided with a pin 20 which is rigid with said rod 16 and projects through the slot 15. At 21 is a flexible metallic wirelike element one end of which is rigidly attached by solder or any other suitable means to the pin 20, the opposite end of the element 21 being rigidly affixed by solder or any other suitable means to the upper end of the tubular element 14. The element 21 being long enough to reach from the top to the bottom of the tubular element 14 when the rod 16 is slid downward in the tubular element 14. From experimentation it has been found that in order to obtain the best results in preventing the wire-like element 21 from becoming knotted or tangled during the operation of the rod 16 slipping in the tubular element 14, the wire-like element 21 is attached to the pin 20 and to the upper end of the pipe element 14 at a point 270 degrees around the pipe 14.

On the upper end of the rod 16 and rigid therewith is a stiff wire-like element 22 bent to form a hook 23 to which one end of the fuse device is attached. There are numerous forms of fuse elements which may be employed, such as low melting point wires, ribbons and the like. The type shown in the drawings consists of "pig tail" or flexible copper wire 24, one end of which is tied in any suitable fashion 25 in the hook 23. At 26 and 27 is a pair of resistance wires, the adjacent ends of which are soldered together at 28 with a low temperature solder. The lower end of the wire 26 is rigidly attached to the upper end of the "pig-tail" 24. The upper end of the wire 27 is rigidly attached to the lower end of a second "pig-tail", or flexible copper wire 29.

On the upper end of the tube 10 is a metallic ferrule 30 having an internal shoulder 31 and an upwardly extending portion 32 which is externally threaded to receive a cap 33. Loosely resting on the shoulder 31 and within the extended portion 32 of the ferrule 30 is a plug 34 having a cone shaped hollowed out portion 35 and a hole 36 in the center of said plug, said hole 36 joining the cone like hollow portion at the apex thereof. On the upper side of the plug 34 is an upwardly extending portion with a flange 37 thereon which forms a channel 38 around the upper side of the plug 34. At 39 is a notch in the flange 37. The upper end of the "pig-tail" 29 is passed through the cone opening 35 and the hole 36 then pulled upwardly until the pin in the lower end of the rod 16 is lifted to the top of the slot 15 in the tube 14 and the spring 17 has been expanded and the tension thereof is pulled on the fuse elements 24, 26, 28, 27 and 29 at which time the "pig-tail" 29 is bent over and caught in the notch 39 and passed around in the channel 38 and tied to temporarily hold against the tension of the spring 17. The cap 33 is now screwed on the portion 32 of the ferrule 30 so that the interior top of the cap presses against the "pig-tail" 29 and firmly binds it between the cap and the flange 37. The plug 34 above described functions as a centering device or means of holding the fusible portion 28 on the center axis of the tube 10 so that when the fuse heats it is not in contact with or close to the wall of the tube 10 thereby preventing burning or charring the material forming the tube. Numerous other fuse centering devices may be employed therefor, this one is merely shown as an illustration of a fuse centering device.

The plug 13 fits well up into the flared portion 12 of the ferrule 11 leaving an edge 40 acting as a drip to prevent ice forming between the plug 13 and the ferrule 11 which might tend to resist the plug 13 being expelled from the ferrule 11. It may be desirable in certain cases to have the plug 13 extend beyond the ferrule 11 as a means of tapping the plug into place so that it will stick while the fuse is being loaded, or to have it extend beyond the ferrule as an indication of whether or not the fuse has operated.

At 41 and 42 are metallic clips adapted to receive the metallic ferrules 11 and 30 and to which are attached the conductors 43 and 44 which are joined together by my fuse device for purposes above described.

In large fuse assemblies it may be desired to reduce weight and this might be accomplished, in part at least, by making the rod 16, in Fig. 2 of a light weight material 16a, in Fig. 8, which is a non-conductor of electricity, in which case it is necessary to provide a metallic connection between the wire 22 of the hook element 23 and the flexible wire element 21. This is taken care of by a conducting material 45, which may be a solid wire, a strip of sheet metal or a flexible wire, etc., one end of which is rigidly attached to the wire 22 and the other end being rigidly attached to the pin 20a which is affixed to the rod 16a and slides in the slot 15 in the tube 14, one end of the flexible metallic element 21 being connected to the pin 20a and the other to the tube 14 as previously described in Fig. 2.

In case a sudden overload of electric current should be imposed upon the conductors 43 and 44 by means of a short circuit or the like, the wires 26 and 27 would become suddenly heated by the electric current, and the solder 28 would

be heated and melted with such rapidity that it might even pass off in a gaseous form; even the wires 26 and 27 might be similarly affected, and raise a gas pressure in the tube 10 and blow the plug 13 and its attached parts out of the tube 10. There is another action taking place simultaneously with that just described. It is as follows: Upon the rupture between the wires 26 and 27, the spring 17 contracts, driving the rod 16 downward until the lower end of the rod 16 strikes the plug 13, as shown in Fig. 5, causing an impact thereon and driving the plug 13 out of the ferrule 11, thereby clearing the tube 10 of all metallic material and leaving a gap in the circuit the length of the tube 10 which is too much for the current to jump or arc thereby effecting a certain and positive break in the circuit.

There are circumstances where the overload on the conductors 43 and 44 is brought on gradually and the violent destruction or blowing of the fuse as above described does not occur, instead, the overload slowly increases and the wires 26 and 27 gradually heat and eventually reach a point where the tension of the spring 17 pulls the wires 26 and 27 apart, whereupon the impact of the rod 16 on the plug 13 instantly takes place and the plug 13 and attached parts are driven out of the tube 10 leaving a gap the length of the tube 10 in the circuit as previously described.

In Figs. 2, 5 and 8 are shown the plunger type of impact producing mechanism, while in Fig. 7 is shown a simpler form to accomplish the same result. Referring to Fig. 7, is shown the tapered plug 13a, which corresponds to the plug 13 in Fig. 2, and rigidly attached to the plug 13a is a metallic spring element 17b, said spring element 17b having a hook like portion 23b formed on the top end thereof to which the "pig-tail" is tied as previously described.

In all of the types of impact producing devices shown, the impact is sufficient to throw the whole impact producing device out of the tube 10 and leave it free of any metallic material, this operation will occur even though the tube 10 may occupy an inclined or even an inverted position.

Inasmuch as the impact producing mechanism is expelled from the tube 10 with such force as above described, the device becomes still more useful. It may enter the field of setting off alarms, or other trains of action such as illustrated in Fig. 9 in which the fuse has been blown and the impact producing device has been driven from the tube 10 and the plug 13 strikes the handle or blade 46 of a switch driving the blade 46 to contact the element 47 to complete a circuit between the conductors 48 and 49 to operate signals, relays or other desired devices. The element 46 might be a trigger which when struck by the plug 13 would release a circuit breaker thereby opening all phases of a poly-phase circuit; or the element 46 might be a trigger which when struck by the plug 13 would release a train of mechanical actions or the like.

The characteristics of my fuse device are such that the device may be employed in fields other than electrical, for instance, the walls of one end of the tube might be left open at 10x so that external flames of fire or heat would melt the fusible link 28 and release the impact producing device and the plug 13 would strike a fire alarm switch such as illustrated in Fig. 9 and close the switch and thereby send out a fire alarm; or the plug 13 might strike a trigger 46 or 46' in Fig. 10

to release fire extinguishing devices 50 of one character or another.

In Fig. 10 is shown my fuse device in which the tubular element 10 is provided with openings 10x, as above mentioned, thereby leaving 5 the fuse 28 open to exterior conditions. As shown the fuse has been melted by outside heat as from a flame, not shown, and the sealing plug 13 has been driven from its seat in the element 11 and has struck the trigger 46' which retained 10 an arm 51 in the dotted position 51'. The arm 51 is mounted on a shaft 52 which is adapted to turn in a clockwise direction, when the arm 51 is released, by reason of the weight 53 which is suspended by a cable 54 which is attached to the 15 sector 55 which is rigidly attached to the shaft 52. On the shaft 52 is a series of arms 56, 57, and 58 all of which are rigidly mounted on the shaft. At 59 is a link connecting between the arm 56 and an electric switch 57 and is adapted to close 20 the switch to complete a circuit upon the rotation of the shaft 52.

At 60 is a shaft having a crank 61 on which is a connecting rod 62. On the shaft 60 is rigidly mounted an element 63 having a stop notch 64. 25 The shaft 60 is adapted to be rotated by any source of power, as illustrated, the source of power is a cable 65 wrapped around the shaft 60 and on one end of the cable is a weight 66. At 67 is a stop bar adapted to catch under the 30 notch 64 and prevent the rotating of the shaft 60. One end of the stop bar 67 is pivotally connected at 68 to the arms 57 which, when the shaft 52 is turned, draws the bar 67 from engagement with the notch 64 thereby permitting rotation of 35 the shaft 60.

At 50 is a water valve having an operating arm 69 which is connected to the arm 58 by the link 70 and upon rotation of the shaft 52 the valve 50 is opened to permit the flow of water 71. 40

The above description of these three operations is only illustrative of a train of operations that can take place as a result of the failure of the fuse 28.

It will be understood that all such modifications of my improved fuse device as have been mentioned above as well as those which lie within the scope of the appended claims may be employed without departing from the spirit and intention of my invention. 45

Now having fully described my invention, what I now claim and desire to secure by Letters Patent is:

1. In an electrical fuse device, a non-conducting enclosure, contact elements on the ends of 55 said enclosure, a fuse element, means in one of said contact elements to hold said fuse element on the central axis of the said enclosure, means in the other contact element to receive a sealing plug, a spring actuated impacting device on said 60 sealing plug and means for attaching said fuse element to said impacting device so that the tension of the spring in the impacting device will hold the fuse element under tension and hold the sealing plug in position in the contact element 65 for the purpose described.

2. In an electrical fuse device, a non-conducting enclosure, contact elements on either end thereof, said contact elements being joined together by the combination of a fusible element 70 and an impact producing device, said fusible element and impact producing device being contained in said enclosure, said impact producing device comprising a plug which fits snugly in one of said contact elements to form a comparatively 75

- weather-proof joint between said plug and contact element, a tubular element rigidly attached to said plug and having a slot in the side of said tube, a rod slidable in said tube and a spring connected between said tube and rod for causing said rod to strike said plug and drive the plug out of its socket in the contact element, a pin on said rod, said pin passing through said slot and adapted to slide up and down therein, and a flexible connection between said pin and said tubular element, means on the upper end of said rod for connecting a fuse element thereto, means for tensioning said spring through said fuse element and means for attaching said fuse element to its respective contact element so that upon the failure and rupture of said fuse element the said rod will be released and caused to strike the said plug by reason of the spring action and drive the plug and its associated parts from its socket and clear the enclosure of all metallic material, substantially as described and for the purpose set forth.
3. In a fuse device, an elongated housing having openings therein intermediate its ends, a fuse element in said housing, said fuse element being exposed to the exterior of said housing through said openings, means in one end of said housing for the support of said fuse element, a spring actuated impacting device in the opposite end of said housing secured to one end of said fuse element and normally held in operative position thereby, said spring actuated impacting device being driven from the housing upon the rupture of said fuse element.
4. In an electrical fuse device, a non-conducting housing, an electrical contact element on each end of said housing, a fuse element and a spring actuated impacting device in said housing, a closure member carried by said impacting device for sealing one end of said housing, said fuse element, spring actuated impacting device and closure member forming an electrical connection between said electrical contact elements, said spring actuated impacting device and said closure member being held under spring tension in said housing by said fuse element so that upon the rupture of said fuse element the spring actuated impacting device will release said closure member and be driven therewith from the said housing.
5. In an electrical fuse device, an insulation enclosure, contact elements on the enclosure, a fuse element, means associated with one of said contact elements to hold said fuse element in spaced relation with said enclosure, a trigger releasing member associated with the other contact element, an impact member on said trigger releasing member, spring means for biasing said impact member towards said trigger releasing member and means for attaching said fuse element to said impact member so that said spring means will normally hold the fuse element under tension and hold the trigger releasing member in position against actuation, said spring means being effective to cause said impact member to strike said trigger releasing member to actuate the latter upon destruction of the fuse element.
6. In an electrical fuse device, an insulating enclosure, contact elements in spaced relation on the enclosure, a fuse element, means associated with one of the contact elements to hold said fuse element in spaced relation within said enclosure, means on the other contact element to receive a sealing plug, a spring actuated impacting device associated with said sealing plug, and means for attaching said fuse element to said impacting device so that the spring of the impacting device will normally hold the fuse element under tension and hold the sealing plug in position in the enclosure, said spring being effective to cause actuation of the impacting device when the fuse is disrupted.
7. In an electrical fuse device, a tubular enclosure of insulating material, a contact element adjacent each end of the enclosure, a fusible element within said enclosure, means for securing one end of said fusible element to one of said contact elements, a closure member adapted to normally engage said other contact element, a spring actuated impacting device carried by said closure member and extending into said tubular enclosure and means for attaching the other end of said fusible element to said impacting device so that the tension of the spring in said impacting device will hold the fusible element under tension and hold said closure member in position with respect to said other contact element.

JUNE L. LEHNHERR.
